FIG.1

FIG.2

FIG.3

FIG.4

FIG. 5

FIG. 6

FIG. 7

FIG. 8

FIG. 1 is a front elevational view of a nozzle showing my new design;

FIG. 2 is a side elevational view thereof;

FIG. 3 is a rear elevational view thereof;

FIG. 4 is a side elevational view thereof taken from the left hand side of FIG. 4;

FIG. 5 is a view similar to FIG. 1 but showing the nozzle head in adjusted position to the left;

FIG. 6 is a view similar to FIG. 5 but showing the nozzle head in adjusted position to the right;

FIG. 7 is a top plan view, on an enlarged scale, of the nozzle of FIG. 1; and

FIG. 8 is a bottom plan view, on an enlarged scale, of the nozzle of FIG. 1.

The dominant features of my design reside in the portions shown in full lines.

I claim:

The ornamental design for a nozzle for use on lawn sprinklers or similar articles, as shown and described.
